Attorney.

UNITED STATES PATENT OFFICE.

DANIEL H. YOUNG AND CHARLES W. PORTER, OF MANCHESTER, IOWA; SAID PORTER
ASSIGNOR OF ONE-HALF OF HIS RIGHT TO GRANT BRAYTON, OF MANCHESTER,
IOWA.

HUMIDIFIER.

1,267,491.

Specification of Letters Patent. Patented May 28, 1918.

Application filed April 16, 1917. Serial No. 162,590.

To all whom it may concern:

Be it known that we, DANIEL H. YOUNG and CHARLES W. PORTER, citizens of the United States of America, and residents of Manchester, Delaware county, Iowa, have invented certain new and useful Improvements in Humidifiers, of which the following is a specification.

Our invention relates to improvements in humidifiers, and the object of our improvement is to supply regulatable, evaporating means suitable for producing a constant supply of vapor to any inclosure.

This object we have accomplished by the means which are hereinafter described and claimed, and which are illustrated in the accompanying drawings, in which Figure 1 is a perspective view of our complete humidifier; Fig. 2 is a plan view of the receiving- 10 tank, with the supply tank removed; Fig. 3 is a vertical transverse section of the boiler and its supporting means, and Fig. 4 is an end elevation of the parts shown in said Fig. 3.

Similar numerals of reference denote corresponding parts throughout the several views.

25 denotes a rectangular receiving tank, open at the top. 28 denotes a rectangular bottle, or supply tank, having a short neck 29, inverted and supported upon the upper end of the tank 25. A cork 30 is fitted into said neck, and a tube 31 passed downwardly through the cork to depend into the receiving tank 35 and upwardly into the supply tank 28 for a short distance.

The numeral 1 denotes a relatively small boiler, closed at the bottom and open at the top, and having in its lower end a nipple 21, 30 the tank 25 having a nipple 23 with a flexible rubber tube 22 fitted over both said nipples to effect communication between the tank 25 and the boiler. The numeral 32 denotes an open-ended casing fitted about the boiler 1, the boiler being slidable lengthwise therethrough, and has an offset part 17. The shaft 16 is mounted within the offset part 17 and has thereon a gear-wheel 14 within the part 17 which engages a rack 13 45 on the adjacent wall of said boiler, said shaft having on its outer end a knurled disk 15.

The numeral 26 denotes an angular clamping body formed of a bar bent medi- 50 ally at a right angle, and having bent over

extremities on which are fixed short pieces of angle-bar 27. One limb of this clamping device is fastened across the casing 17—32 fixedly by means of pins 24. The casing, with its included movable boiler 1, may be 60 removably mounted upon the supply tank 25 by means of this clamping device when the clamping device is positioned as shown in said Fig. 2 with the angle-bars 27 engaging diagonally opposite angles of said tank. 65 In order to prevent loss of heat from the boiler 1 to the tank 25, a plate of suitable material 19, which is a poor conductor of heat, may be cemented or otherwise mounted upon the casing 32 between it and the 70 tank 25, and also there may be an air space between the plate 19 and said tank, a plurality of spaces 20 being used therebetween.

Referring now to Figs. 1 and 3, I have supplied the following described means for 75 heating the fluid contents of the boiler 1 to a degree sufficient for rapid evaporation or even boiling: This means consists of a pair of spaced electrodes 3 and 4, whose extremities are fixed in a block of insulation 5. 80 Said electrodes are positioned dependingly within the boiler 1 so as to be immersed a considerable portion of their lengths in the fluid contents thereof. The upper ends of said electrodes are bent oppositely at right 85 angles and carried outwardly through slots 2 in the upper end of the boiler. The numerals 6 and 7 denote insulating sleeves mounted on the bent over ends of the electrodes to contact with the inner and outer 90 walls of the boiler. The bent over ends of the electrodes are threaded to receive knurled discoidal nuts 8 and are employed to secure conductor terminals 9 and 10 in electric contact with the electrodes 3 and 4 respectively, 95 as also to clamp the insulating sleeves 6 and 7 tightly upon the boiler walls, it being understood that the electrodes, in passing through the slots 2, are kept out of contact with said boiler. The conductors 9 and 10 100 may be placed in circuit with any source of electrical current of sufficient capacity such as the three-phase alternating generator 12.

When the bottle or reservoir 28, after having been filled with water and the closure 30 put in place, has been inverted and positioned upon the top of the supply tank 25 with the tube 31 depending thereinto, said tank becomes partially filled with water, and the water level is constantly maintained 110

by reason of the operation of the well-known law, until the reservoir is emptied. Water flows from the tank 25 by way of the flexible conduit 22, into the boiler 1, partially immersing the electrodes 3 and 4 therein. When the switch 33 is actuated in one direction, circuit is closed from the generator 12, conductors 9 and 10, and electrodes 3 and 4, through the fluid in the boiler 1, and the resistance of the latter results in its being rapidly heated to the boiling point. When desired, vapor or steam issuing from the open upper end of the boiler may be deflected horizontally by means of an open-ended hood 11 removably mounted in said boiler opening.

The heating of the fluid within the boiler may be expedited or retarded, as the case may be, by actuating the rack and pinion mechanism to either lower or elevate said boiler relative to the supply tank 25, which causes more or less of the lengths of said electrodes to be immersed in the fluid in the boiler because of the varying quantity of said fluid occasioned by said adjustment.

The casing 32 is preferably split vertically at 18 along its end opposite to the offset part 17 to permit of the passage of the nipple 21 through the slit 18.

30 The conduit 22, being relatively long and flexible, permits of enough vertical movement to said boiler 1.

Various modifications may be made in our humidifier, and other means of heating the boiler contents resorted to, without departing from the principle of our invention.

Attention is particularly called to the fact that while the supply tank 25 is very capacious, the boiler 1 is of relatively limited capacity, permitting the contents of the lat-

ter to be speedily heated without loss of heat to the contents of said tank. The device is especially adapted to humidify the atmosphere in such inclosures as cigar-cases, and electric current may be conveniently applied by using the ordinary 110-volt lighting circuit.

In Fig. 1 we have shown an encircling receptacle 34 about the boiler 1, which is located just below the top of the boiler, to catch any water boiling over therefrom.

Having described our invention, what we claim as new, and desire to secure by Letters Patent, is:

1. A humidifier, comprising a relatively small vessel open at the top, a relatively large supply-tank in communication therewith, and electrodes adjustably positioned within said vessel and in circuit with a source of electric current.

2. A humidifier, comprising a relatively large supply-tank, a relatively small boiler positioned near it, a casing in which said boiler is movably mounted, a clamping-device detachably securing said casing upon said supply-tank, and a body positioned between said boiler and tank which is a poor conductor of heat.

3. A humidifier, comprising a relatively small boiler, a relatively large supply-tank in communication therewith, a casing in which said boiler is movable, operative mechanism mounted in said casing for moving said boiler relatively to said supply-tank, and means positioned within the boiler to heat its contents.

Signed at Waterloo, Iowa, this 30th day of March, 1917.

DANIEL H. YOUNG.
CHARLES W. PORTER.
